Specification of Letters Patent. Patented Aug. 13, 1918.

Application filed April 13, 1914. Serial No. 831,556.

To all whom it may concern:

Be it known that I, JOHN SCHNEIDER, residing at New York, in the county of New York and State of New York, have invented 5 certain new and useful Improvements in Switches, of which the following is a specification.

This invention relates to a switch particularly adapted for the control of high 10 tension electric currents.

It is well known that a heavy and objectionable spark occurs upon the breaking of a high tension line. For this reason it has been the practice heretofore to construct 15 switches for this purpose so that the spark producing parts are submerged in oil to the end that the spark may be avoided. These constructions are unreliable, expensive and troublesome.

20 An object of the present invention therefore is to provide a switch by means of which a line may be broken in air, and by means of which the ensuing spark may be readily and positively dissipated in a manner thoroughly satisfactory.

25 A further object to is provide a switch by means of which the spark producing terminals or parts are adapted to give a "throwing off" effect to the spark at the moment of its appearance.

30 A further object is to provide means for giving definite and proper direction, and for imparting a dissipating influence upon the spark, at the moment of and following its inception.

35 Other objects and 5 of the invention, more or less specific in those referred to above, will be in part obvious and in part pointed out in the course of the following 40 description of the elements, combinations, arrangements of parts and applications of principles, constituting the invention; and the scope of protection contemplated will be indicated in the appended claims.

45 In the accompanying drawings which are to be taken as a part of this specification, and in which I have shown a merely preferred form of embodiment of the invention:

50 Figure 1 is a side elevational view of a switch constructed in accordance with the principles of this invention;

Fig. 2 is an elevational view taken at right angles to the view shown in Fig. 1,

illustrating a battery of switches connected 55 for simultaneous operation;

Fig. 3 is an enlarged detailed view of one of the switches and the mountings therefor, parts being illustrated in vertical section 60 for disclosing structural details;

Fig. 4 is a top plan view of the structure illustrated in Fig. 3; and

Figs. 5, 6, 7, 8, 9, 10, 11, and 12 illustrate modifications.

Referring to the drawings for a detailed 65 description of the structure illustrated, the reference character L indicates a base plate upon which the switch or switches are mounted. The base plate L may be carried upon any suitable support, but preferably 70 is carried at the upper end of a tower G so that the mechanism carried by the base plate is elevated to a proper level for safety.

Since each of the switches in the battery, 75 illustrated in Fig. 2, is identical in its construction and operation, one only thereof will be described.

Mounted upon the upper surface of the base L is a plurality of insulators 1, 2, 3 and 4. These may be of any suitable type. 80 A plate 5 is mounted upon the upper ends of the insulators 1 and 2, and a similar plate 6 is mounted upon the upper ends of the insulators 3 and 4. All of the insulators are preferably arranged in a row, and insulators numbered 2 and 3 are spaced a suitable distance apart. The plate 5 carries a pivot pin 7 upon which is mounted a contact blade 8 projecting toward the insulator 3, but terminating short thereof and 85 being adapted to swing upwardly. The plate 6 carries a pivot pin 9 upon which is mounted a contact blade 10 projecting toward the insulator 2, but terminating short thereof and being adapted to swing upwardly.

90 The outer end of the contact blades over-lap each other when in horizontal position, as indicated in full lines in Fig. 3, and one thereof, as the blade 8, is bifurcated to receive the lapping portions 95 of the other thereof, as 10.

The contact blades 8 and 10 are each formed with an upwardly extending arm 11. Links 12 extend from said arms to crank arms 13 carried upon operating shafts 14.

100 The shafts 14 are connected to be simultaneously operated by a controlling handle H arranged at a suitable point for conven-

ient operation by an operator standing upon the ground, and the portions of said shafts to which the crank arms 13 are connected, are insulated from the remaining portions by 5 the insulators 1 and 4. The particular manner of interposing the insulators 1 and 4 is not essential to this invention, but, that illustrated may be described as including a pair of standards 15 and 16 rotatably 10 mounted upon the upper surface of the base L and having the insulators 1 and 4 respectively rigidly connected to rotate therewith, the insulators being provided with sockets 17 in their lower ends into which 15 the upper ends of the standards are cemented. Sockets 18 are formed in the upper ends of the insulators into which pins are fixed. The pins project upwardly from the upper ends of the insulators, through bearing apertures 18 formed in the plates 5 and 6 and carry the crank arms 13 above said plates. These pins may be referred to as 20 the ends of the operating shafts.

The standards 15 and 16 have attached 25 thereto socket members 20 and 21 respectively projecting downwardly therebeneath and through bearing apertures 22 formed in the base L. The socket member 20 carries a short shaft 23 to which is attached a 30 crank arm 24, the socket member 21 carries a short shaft 25 to which is attached a crank arm 26. The crank arms 24 and 26 are connected by a link 27 so that movement of one crank arm imparts a similar movement to the other.

Where a battery of switches is to be operated, for instance as illustrated in Fig. 2, the short shaft 25 of each of the switches has attached thereto an additional crank 40 arm 28, and said crank arms 28 are connected for simultaneous operation by means of links 29. Any number of switches may thus be connected in a battery.

In order to operate, the control handle 45 H may be connected to any one of the switches in the battery, but, as illustrated, is connected to the intermediate switch of the three illustrated. The manner of connection simply includes a shaft 30 fixed to 50 and rotatable with the handle H by its lower end and being attached to, or formed as a continuation of, the short shaft 25 of said intermediate switch.

The lower end of the shaft 30 projects 55 through a bearing plate 31 and the operating handle H is arranged beneath said bearing plate and is preferably formed with a tongue 32 for engaging with a notch 33 formed in the under side of said bearing 60 plate when the handle is moved to position for opening the switch or switches. Obviously two or more notches 33 may be provided for retaining the handles in their positions, if desired. The handle is obviously 65 connected to swing in a vertical plane, and

the tongue 32 disengages from the notch or notches 33 when the handle is swung to horizontal or operating position. When the desired movement of the switch or switches has been accomplished, then the handle is 70 lowered and the tongue 32 enters one of the notches 33 to retain the switches in that position so long as the handle remains lowered.

It will be understood that rotation of the shaft 30 rotates all of the insulators 1 and 4 and swings all of the arms 11 outwardly and all of the contact blades 8 and 10 upwardly with a simultaneous movement. As the contact blades swing upwardly, their lapping portions disengage from each other, the spark produced by the disengagement however is produced at a moment when the blades are moving upwardly at a greater or less speed, and will naturally be influenced by this motion and be thrown off upwardly. 85 Both of the blades being in movement, there will be no tendency for the spark to hang on, as is the case where one of the blades is stationary, as is common.

In order to protect the ends of the blades 90 from being burnt by the spark, and in order further to more effectively dissipate the spark, it is a part of this invention to provide dissipating horns 34 and 35, preferably one upon each of the blades and movable 95 therewith. These horns are extended along the side of the blades in lapping engagement, as best shown in Fig. 4, to a point slightly beyond the ends of the respective blades whence they are bent upwardly at an 100 obtuse angle substantially as indicated in Fig. 3. As the blades move upwardly to break the circuit the horns remain in contact until after the blades have moved a little distance apart, as indicated by the 105 light dotted lines in Fig. 3. The resultant spark appears between the horns therefor rather than between the blade so that the horns will receive the damage, if any, incident to the heat of the spark. As the 110 blades are moved farther apart toward the fully opened position, as indicated by heavy dotted lines in Fig. 3, the spark will be thrown off in the same manner as if directly between the blades, except that the angular 115 disposition of the ends of the horns at this time, as suggested by the dotted lines in Fig. 3, will have a dissipating influence thereon which will be readily understood by those skilled in the art.

The horns are relatively inexpensive and are preferably attached to the blades by means, as at 36, which will permit their ready disengagement, for the purpose of renewal or otherwise.

The structures illustrated in Figs. 5 to 10 indicate various ways in which this invention may be carried out for producing results of like kind to those heretofore described. The efficiency of these modified ar- 125 130

rangements, however, is not at this time believed to be as great as that shown in Figs. 1 to 4.

In Fig. 5, the horns 37 and 38 are shown to be stationary rather than movable with the contact blades as in Figs. 1 and 3. In this instance the contact blades separate, and though the spark is produced directly between the end portions of said blades, these portions of the contact blades move almost immediately into position, as indicated in dotted lines of Fig. 5, where the spark is transferred to the horns. The contact blades may be in rubbing contact with the horns throughout their movement if desired, though where the horns are in electrical contact with the supporting plate of the blades as illustrated, it is not necessary to provide an actual rubbing contact. In operation the movement of the contact blades toward the position shown in dotted lines imparts a certain movement or throwing off effect to the spark which causes the spark to travel upwardly and be dissipated between the upwardly diverging portions of the horns, in the same manner as obtains in Figs. 1 and 3.

The structure in Fig. 6 is substantially the same as that shown in Fig. 5, the only difference being that in this instance the contact blades move to a definite position, in which they strike against properly shaped portions of the horns, and in which their faces as 39 form continuations of the faces of the horns.

The structure in Fig. 7, shows one of the horns as 40 to be stationary, and the adjacent contact blade as 41 to be movable adjacent thereto, as in Fig. 5, whereas the other horn is carried by and movable with the other contact blade, as in Figs. 1 and 3. In the open position of the contact blades the horns occupy substantially the same positions as in the former figures, and the result is of the same kind.

In the structure of Fig. 8, one movable contact as 42 only is employed. This contact moves into the same relative position to a horn 43 as in the structure of Fig. 5, the horn being stationary. The other horn as 44 is also stationary with a stationary contact 45, and is arranged adjacent to the end of the movable contact, so that as said movable contact swings upwardly, said end thereof will draw gradually away from the horn 44. The resultant spark will lengthen and move upwardly as the contact 42 moves and when the end of the contact 42 reaches the position indicated in dotted lines the upward momentum or throwing off influence imparted to the spark will induce it to continue its upward movement along the diverging portion of the two horns as in the other figures.

The structure shown in Fig. 9, is some-

what similar to that shown in Fig. 8. The essential difference being that the horn 46 for the movable contact 47 in Fig. 9, is carried by and movable with said contact. The operation and result is the same as in Fig. 8.

The structure shown in Fig. 10, includes a stationary contact 48, and a movable contact 49, engaging therewith as in Fig. 8. In this instance the movable contact carries a horn 50, said horn being movable with the contact 49. The opposing horn, as 51, is pivotally mounted in a bearing 52, to swing upwardly in unison with the movement of the horn 50.

In the structure shown in Fig. 11, the contact blades 53 are mounted upon pivotally supported insulators 54. Arms 55 are connected to the insulators and project toward each other. The adjacent ends of the arms are pivotally connected to the member end of a push rod 56. The hand lever 57 is arranged for moving the rod 56 to swing the insulators about their pivots. Horns as 58 are attached to the blades 53, preferably in the same manner as shown in Fig. 1, though in this modification a horn bent backwardly, as indicated, so that when the insulators are swung to separate the blades 53, the horn will stand in proper diverging relation.

It is not entirely essential to this invention that the blades swing upwardly so long as the horns are employed, for the horns will produce, in a measure, the same result of inducing the spark to travel upwardly.

It is also contemplated that an adjustable counterweight, such as illustrated at 58 in Fig. 12, may be employed in connection with the moving contact blades for assisting the movement and for retaining the blades in circuit braking position after they have once been moved to such position.

As many changes could be made in this construction without departing from the scope of the following claims, it is intended that all matter contained in the above construction or shown in the accompanying drawings shall be interpreted as illustrative only and not in a limiting sense.

Having thus described my invention what I claim as new and desire to secure by Letters Patent, is:

1. A switch comprising a pair of contact blades projecting toward each other having their adjacent end portions contacting, the opposite ends of said contact blades being pivotally mounted, means for swinging said blades about their pivotal mountings to move their adjacent ends out of contacting relation, including arms formed upon said contact blades, links connected to said arms, a pair of rotatable members having crank arms to which said links are connected respectively, and means for simultaneously operating said rotatable members for simul-

taneously operating both of said contact blades.

2. A switch comprising a pair of contact blades projecting toward each other having 5 their adjacent end portions contacting, the opposite ends of said contact blades being pivotally mounted, means for swinging said blades about their pivotal mountings to move their adjacent ends out of contacting 10 relation, including arms carried by said contact blades, links connected to said arms, a pair of rotatable members having crank arms thereon to which said links are connected respectively, means for rotating one 15 of said rotatable members, other crank arms formed on said rotatable members, and a link connecting said last crank arms to impart movement of one to the other for simultaneously operating both of said contact 20 blades.

3. A switch comprising a pair of contact blades projecting toward each other in a substantially horizontal plane having their adjacent end portions contacting, the opposite ends of the contact blades being pivotally 25 mounted to permit the contact blades to swing in a vertical plane into and out of contacting relation, and means for swinging said contact blades about their pivotal mountings comprising laterally extending 30 arms formed upon said contact blades, a pair of vertically arranged rotatably mounted operating shafts one adjacent each of said contact blades, crank arms carried by said operating shafts, links connecting said crank arms with the laterally extending arms of the contact blades, other crank arms carried by said operating shafts, a link connecting said last mentioned crank arms together whereby rotary movement of one of 35 said operating shafts will rotate the other operating shaft, and means whereby the first mentioned operating shaft may be manually rotated at will.

In testimony whereby I affix my signature 40 in the presence of two witnesses.

JOHN SCHNEIDER.
